DESIGN FOR A SHOE

Bertram V. Fister, Elmhurst, N. Y.

Application March 30, 1934, Serial No. 51,262

Term of patent 3½ years

To all whom it may concern:

Be it known, that I, BERTRAM V. FISTER, a citizen of the United States, residing at Elmhurst, in the county of Queens and State of New York, have invented a new, original, and ornamental Design for Shoe, of which the following is a specification, reference being had to the accompanying drawing, forming part thereof.

I claim:

The ornamental design for a shoe, as shown.

BERTRAM V. FISTER.
